George W. Springsted

UNITED STATES PATENT OFFICE.

GEORGE W. SPRINGSTED, OF NEW YORK, N. Y.

BLIND-SLAT ADJUSTER.

SPECIFICATION forming part of Letters Patent No. 268,835, dated December 12, 1882.

Application filed July 17, 1882. (No model.)

To all whom it may concern:

Be it known that I, GEORGE W. SPRINGSTED, of the city, county, and State of New York, have invented a new and useful Improvement 5 in Blind-Slat Confining and Adjusting Devices, of which the following is a full, clear, and exact description, reference being to the accompanying drawings, in which—

Figure 1 shows a cross-section of the blind 10 through the slat-holding device, the slats being open; Fig. 2, a front view of the blind, the slat-rod being up; Fig. 3, a view of the slat holding and adjusting device from below.

My invention relates to an improvement in 15 devices for confining and adjusting the slats of blinds in any desired position.

In the drawings like letters indicate like parts.

A A is the frame of the blind.

20 B B are the slats.

C is the slat-rod.

D is a metallic tip or socket, fastened to the 25 end of the slat-rod. In the lower end of it there is a thread cut in a hole therein to match into a thread cut on the adjusting-rod I, as hereinafter explained.

E is a friction-wheel sustained in the metallic frame or case L L, which is inserted in a mortised recess in the frame A of the blind by 30 the bent end of the lever H. The wheel E is rigidly attached to this bent end of the lever H, which serves as a shaft or axis for the wheel E. This lever H passes through a portion of the metallic case L, as seen at f in Fig. 3, and the 35 other end of it at the other side of the wheel is supported by another portion of the case. (Seen in the same figure at g.)

F is a friction clutch or brake, which is pivoted to the case L, and has a set-screw, G, 40 threaded into the lower end thereof, by which the pressure of the upper end of the brake upon the friction-wheel E is regulated. H is a lever, the lower end of which is bent at right angles and forms the axis of the friction-wheel E, as stated.

I is the adjusting-bar, which is threaded throughout substantially its entire length, and its threads engage with the threads in the lower end of the tip or socket D.

50 K is a ring or link, which is swiveled to the lower end of the adjusting-bar I, so that it is capable of a swinging motion upon it, substan-

tially as the chain-ring of a watch is attached to the stem thereof.

L is the case or frame of the slat-holding device. It is made in the outline shown in Fig. 3, (this being a view of it from below,) and has in its central portion a recess, n, which is received in the deepest part of the mortise in the frame A, and into this recess n the end of the 55 slat-rod C and the lever H and the adjusting-rod I swing when the slats are turned completely down. I prefer to provide a top plate, m, for the case L, which is let into the upper surface of the frame A, the better to finish off 60 the case L, add to its appearance, and also to inclose and protect the friction-wheel.

The operation is as follows: All the parts being fastened in their positions, as shown, the lever H passing through the ring or link K, 70 which is of such size as to receive it somewhat snugly, so that there may be but little play of the parts, to avoid rattling, the friction clutch or brake is set somewhat strongly against the friction-wheel, so that in whatever position the 75 slat-rod is left the friction-wheel will hold it, and, as the slat-rod is moved up or down, the ring K, being acted on by the lever H, will swing from a substantially horizontal position from the adjusting-rod I outwardly from the 80 blind when the slat-rod is most elevated to a corresponding position inwardly toward the blind when the slat-rod is most depressed. The friction clutch or brake F may be tightened or loosened by the set-screw G at will. 85 The adjusting-rod is threaded, so that the device may be made to fit and properly operate with different sizes of blinds or with blinds of unusual relative proportions between the slat-rod and the lower bar of the frame A. If the 90 adjusting feature is not desired, then the ring K or an equivalent device for engagement with the lever H may be attached directly to the end of the tip D, and instead of the adjustable friction clutch or brake F a spring may be 95 attached to the case L and made to bear upon the friction-wheel E.

I do not limit myself to the precise details of construction as shown, for they may be somewhat departed from and still my invention be 100 embodied.

I claim as new—

1. The combination of the slat-rod C, the tip D, the threaded adjusting-rod I, the ring K,

the lever H, the wheel E, the friction-bar F, the screw G, and the case L, substantially as and for the purposes set forth.

2. The combination of the tip D, the adjusting-rod I, the ring K, the lever H, the wheel E, and the spring F, substantially as and for the purposes set forth.

3. The combination of the lever H, the wheel

E, the friction-bar F, the set-screw G, the case L, and suitable means for connecting the lever H with the slat-rod, substantially as and for the purposes set forth.

GEORGE W. SPRINGSTED.
